UNITED STATES PATENT OFFICE.

SAM CORTESE, OF DUNSMUIR, CALIFORNIA.

SEWING IMPLEMENT FOR LEATHER GOODS.

Application filed March 1, 1922. Serial No. 540,239.

To all whom it may concern:

Be it known that I, SAM CORTESE, a citizen of the United States, residing at Duns-
muir, in the county of Siskiyou and State of
5 California, have invented certain new and
useful Improvements in Sewing Implements
for Leather Goods, of which the following
is a specification.

My invention relates to devices to be used
10 by cobblers and saddle makers for sewing
leather goods by hand and the main object
of the invention is to provide such an im-
plement, by means of which not only the
holes are pierced in the layers of leather to
15 be sewed together, but also the actual sew-
ing is performed at the same time. That is
to say, the operator uses only one tool, which
he does not lay aside after a hole has been
pierced, as is usual in ordinary leather stitch-
20 ing, but retains it in his hand to pass a
thread through a hole previously made and
lock the threads together to form a stitch.

The advantage of using such a tool is
evident, as considerable time is saved as
25 well as labor, permitting the operator to
concentrate his mind upon the work.

Another object of the invention is to make
the implement of such a shape, that it lies
snugly and comfortably in the operator's
30 hand.

Still another object of the invention re-
sides in the fact, that the tool forms a re-
ceptacle for a bobbin for the under thread
used in lock stitching.

35 Lastly an object of the invention is to
provide the implement with twin needles,
one longer than the other; the shorter one
being placed in advance of the longer one in
order to pierce a hole for the latter, which
40 simultaneously is made to pass through a
previously made hole and to return with the
thread from the upper side of the work. As
the two needles always pass together through
the layers of leather, the spacing of the
45 stitches becomes uniform throughout, so
that the stitching will have the appearance
of machine stitching and be just as uniform
as the latter.

Other objects and advantages will occur in
50 the following detailed description of the
device.

The implement is illustrated in the accom-
panying drawings; and

55 Figure 1 shows the device in perspective
view at the time a thread has been drawn
through the work;

Figure 2 is a similar view to Figure 1 in-
dicating the manner in which a lock stitch
is formed;

Figure 3 is also a perspective view with 60
the implement open;

Figure 4 is a transverse section thereof;

Figure 5 shows in perspective view one
of the details;

Figure 6 is a perspective view of a bobbin; 65

Figure 7 is a perspective view of the
tensioning device for the under thread; and

Figures 8, 9, 10 and 11 are perspective
views of different forms of needles used with
the implement. 70

The main parts forming the implement
consist of a twin needle 15, a handle 16, a
case 17 and a bobbin 18.

The twin needles are made in different
forms according to the use for which they 75

are intended. In Figure 8 for instance the
needles are shown as straight and comprise
a short prong 19, a long prong 20 and both
joined together by means of a stem 21
adapted to fit tightly in the handle 16 and
secured therein by means of a set screw 22.
This straight needle is intended for use on
saddlery and harness work. The prongs 19
and 20 are parallel with each other and the
shorter prong 19 forms an awl intended to
pierce a hole through the layers of leather
85 to be sewed together. After such a hole has
been produced, the longer prong 20 is made
to pass through this hole while simultane-
ously prong 19 pierces another hole for the
90 next stitch in the work. It will now be
evident that the spacing of these holes will
be exactly alike and just as even as in
machine sewing. The longer prong 20 termi-
nates with a point having a rearwardly di-
rected hook 14 intended for engaging with
95 the upper thread of the work.

The twin needle illustrated in Figures 1
and 9 is of the same character as the one just
described, but is intended to be used by shoe-
makers. For this reason its prongs 23 and
100 24 have a slight bend in the same direction
near the end of the prongs.

The form of the twin needle illustrated in
Figure 10 is of the same character as that
shown in Figure 9 with the difference that
the prongs 25 and 26 are curved along their
entire length.

Sometimes it might be advisable to make
the two needles separate as shown in Figure 110
11 where the awl 27 is also shorter than the
sewing needle proper 28, and both are

mounted in the same or separate sockets in the handle 16 as before.

The handle 16, which consists of a shell 29 and a cover 31 carries the twin needle 15 at 5 one end of the shell and has its largest dimension midway between its two ends and tapers from the middle towards both ends, a socket member 30 gripping the twin needle 15 at one end thereof. At the opposite end 10 a cover 31 is hinged as at 32 so as to swing in a longitudinal plane of the handle. In other words, it folds like a blade in a jack-knife along line 33. The cover 31 and the shell 29 join along a line 33 at one side of 15 the handle where their outer surfaces coincide so as to form a smooth joint. Between the shell 29 and the cover 31 is formed a hollow or chamber 34 which opens outwardly along one side of the handle as at 20 35 and also at the needle end of the handle as at 36. A clasp 37 is provided for securing the cover 31 to the shell 29 when the cover is folded in closed position.

In the hollow or chamber 34 of the handle 25 is deposited the case 17 which is approximately pear shaped and fits loosely in the chamber, in fact it is so loose that it will rattle in the handle and permit a thread to pass over and around it. It terminates with 30 a sharp point 38 which is intended to protrude through the opening 36 adjacent the needle end of the handle as seen in Figures 1, 2 and 3. The case is recessed as at 39 to receive the bobbin 18 and a central stem 40 35 is provided in the recess and around which the bobbin 18 may revolve. The central part of the lid 41 has a thin shank 42 in its center and which is threaded to engage with corresponding threads 43 at the end of the stem 40. This lid 41 is intended to retain 40 the bobbin in position. From the recess 39 a narrow slit 44 is provided in the case 17 running from the recess 39 to a notch 45 near the edge of the case 17. In this notch 45 is seated a tensioning spring 46 secured by means of a screw 47 or in any other suitable manner so as to make the tensioning spring 46 adjustable over a thread passing from the bobbin through slit 44 and between the 50 straight and folded fingers 48 and 49 respectively of the tensioning spring.

The use of the tool is as follows:—After the work 50 has been secured on a suitable work bench and a spool 51 revolvably mounted adjacent to the work on the bench, the operator grasps the handle in one hand with the twin needle 15 pointing in the direction of the work. For the first stitch the awl or prong 23 is pushed through the layers of the 55 leather piercing it and after this has been done, the long prong 24 is pushed through the hole provided, while simultaneously the short prong 23 again pierces the leather to provide the next hole. When the long prong 60 65 24 has been pushed through the work, its

hook 14 engages around the upper thread 52 on the spool 51 whereupon the tool is retracted, when the hook on the prong 24 will draw the upper thread through the work as seen in Figure 1 forming a loop on the 70 thread. Another thread 53, which is wound around its spool 18 deposited in the casing 17 within the handle 16, has its end secured in the work and as a long loop about six or 75 seven inches in length is now formed on the upper thread 52 and laid over the point 38 and around the body of the case 17, it will lock with the under thread 53 from the bobbin, whereupon the two threads are drawn 80 tightly to form a stitch in the work. This operation is thereupon repeated and for the next stitch the prong 24 passes through the aperture 55 previously produced by the short prong 23, which will then produce the 85 hole for the next stitch.

The under thread 53 from the bobbin 18 when passing through the slit 44 is suitably tensioned by means of spring device 46 and thereupon made to pass through the long opening 35 in the handle to the under side of 90 the work.

Having thus described the invention what is claimed as new is:

1. A handle for a needle, said handle having a chamber with a permanently open slit along one side and one end thereof for admitting a looped thread, and a bobbin deposited loosely in said chamber and carrying a second thread adapted to run out through said slit and to lock with said looped thread when the latter passes over 95 said bobbin.

2. A handle for a needle, said handle comprising a shell, a cover for said shell, the cover and the shell forming a chamber between them with a permanently open slit along one side and one end of said handle for admitting a looped thread, and a bobbin deposited loosely in said chamber and carrying a thread adapted to run out through 100 said slit and to lock with said looped thread when the latter passes over said bobbin.

3. A handle for a sewing needle, said handle comprising a shell, a cover for said shell, the cover and the shell forming a chamber between them with a permanently open slit along one side and one end of said handle for admitting a looped thread, a bobbin deposited loosely in said chamber and carrying a thread adapted to run out through 110 said slit and lock with said looped thread when said bobbin passes through the same, said cover being hinged to said shell and having a lock for securing the cover and the shell together.

4. A handle for a sewing needle, said handle comprising a shell, a cover for said shell, the cover and the shell forming a chamber between them with a permanently open slit along one side and one end of said handle for 115 120 125 130

- admitting a looped thread, and a case fitting loosely within said chamber and having a pointed end adapted to protrude through the slit at said end in order to pass through 5 a looped thread admitted through said slit, said case forming a receptacle for a bobbin carrying a second thread adapted to pass through said slit and to lock with said looped thread.
- 10 5. A handle for a sewing needle, said handle comprising a shell, a cover for said shell, the cover and the shell forming a chamber between them with a permanently open slit along one side and one end of said 15 handle for admitting a looped thread, a case fitting loosely within said chamber and having a pointed end adapted to protrude through the slit at said end in order to pass through a looped thread admitted through 20 said slit, said case having a recess, a bobbin carried in said recess, and means for revolvably securing the bobbin therein, said bobbin carrying a second thread adapted to pass through said slit and to lock with said 25 looped thread.
6. A handle for a sewing needle, said handle comprising a shell, a cover for said shell, the cover and the shell forming a chamber between them with a permanently 30 open slit along one side and one end of said handle for admitting a looped thread, a case fitting loosely within said chamber and having a pointed end adapted to protrude
- through the slit at said end in order to pass through a looped thread admitted 35 through said slit, said case having a recess, a bobbin carried in said recess, and an opening being provided in the side of the case communicating with said recess and permitting a thread carried by the bobbin to pass 40 through said opening and said slit and to lock with a loop of another thread passing around said case when admitted through said slit.
7. A handle for a sewing needle, said handle comprising a shell, a cover for said shell, the cover and the shell forming a chamber between them with a permanently open slit along one side and one end of said handle for admitting a looped thread, a case fitting 45 50 loosely within said chamber and having a pointed end adapted to protrude through the slit at said end in order to pass through a looped thread admitted through said slit, said case having a recess, a bobbin carried 55 in said recess, an opening being provided in the side of the case communicating with said recess and permitting a thread carried by the bobbin to pass through said opening and said slit and to lock with a loop of 60 another thread passing around said case when admitted through said slit, and means adjacent said opening for tensioning said thread.

In testimony whereof I affix my signature.
SAM CORTESE. [L. s.]
